UNITED STATES PATENT OFFICE.

FRANK BOWDEN, OF LOWELL, MASSACHUSETTS, ASSIGNOR OF ONE-HALF
TO ARTHUR P. BROWN, OF SAME PLACE.

GRAPPLE.

SPECIFICATION forming part of Letters Patent No. 296,666, dated April 8, 1884.

Application filed February 29, 1884. (No model.)

To all whom it may concern:

Be it known that I, FRANK BOWDEN, a citizen of the United States, residing at Lowell, in the county of Middlesex and Commonwealth of Massachusetts, have invented certain new and useful Improvements in Grapples, of which the following is a specification.

My invention relates to improvements in grapples for lifting barrels, boxes, and bags or other flexible packages.

In the accompanying drawings, Figure 1 is an isometric view of a barrel with my invention upon it; Fig. 2, an isometric view of the grapple; Fig. 3, a view of the handle and section of the band; Fig. 4, a view of the loops used to confine the bands and a section of the latter.

My improved grapple consists of two loops or bands, B B', of metal or other suitable material, so attached one to the other that upon lifting the handles C C' the bands tend to close upon each other in a vertical position, and thus press upon and hold any article placed within them. These bands or loops may be united by means of the staples D D', Figs. 2 and 4, or they may be riveted or screwed together, care being taken that it is done in such a manner that they may turn freely.

The operation of my invention is as follows: The bands are placed about the article to be lifted, and the handles being raised the bands assume the position shown in Fig. 1, and press upon the sides of the package, and thus hold it firmly, the pressure being proportionate to the weight of the package.

For some purposes points e, Fig. 2, may be advantageously used to insure a firm hold; but in most instances the friction exerted by the edges of the bands will be sufficient.

It is evident that there can be many modifications of my invention without departing from the original idea. The part below the dotted line X X in Fig. 1 may be dispensed with, and only two sections of a circle used, these being united in any desired manner, so

that they may turn freely. In such a modification the points e could be used with advantage. When the bands used are loops, the action will be the same whether they are united or not; but if only half loops or sections are used, they must be joined at or near their ends in such a manner as to allow them to turn freely.

It is evident that the bands may be of any desired shape, or may be made of flexible material, so as to more easily adjust themselves to the shape of the article to be lifted.

The handles C C' are made of such a form as to be easily grasped by the hand, or by a loop of rope, or by the ordinary clutch used in loading-tackle.

I claim as my invention—

1. A grapple consisting of two bands or loops provided with handles, and arranged to surround and clasp a package upon being raised by said handle, as and for the purpose specified.

2. A grapple consisting of two bands or loops provided with handles, the inner surfaces of said loops having points or projections, and arranged to surround and clasp a package upon being raised by such handles, as and for the purpose specified.

3. A grapple consisting of two bands or loops, connected to each other by staples, and provided with handles, and arranged to surround and clasp a package upon being raised by said handles, as and for the purpose specified.

4. A grapple consisting of two bands or loops, connected to each other by staples, the inner surfaces of said bands having points or projections, and being provided with handles, and arranged to surround and clasp a package upon being raised by such handles, as and for the purpose specified.

FRANK BOWDEN.
